UNITED STATES PATENT OFFICE.

FREDERICK W. TUERK, JR., OF SYRACUSE, ASSIGNOR OF TWO-THIRDS TO JOHN HUNTER AND JAMES C. HUNTER, 2D, BOTH OF STERLING, NEW YORK.

ROTARY WATER-METER.

SPECIFICATION forming part of Letters Patent No. 362,047, dated April 26, 1887.

Application filed May 29, 1886. Serial No. 203,667. (No model.)

To all whom it may concern:

Be it known that I, FREDERICK W. TUERK, Jr., of Syracuse, in the county of Onondaga, in the State of New York, have invented new 5 and useful Improvements in Rotary Water-Meters, of which the following, taken in connection with the accompanying drawings, is a full, clear, and exact description.

This invention has special reference to the 10 water-meter for which I have obtained Letters Patent of the United States No. 328,544, dated October 20, 1885.

The object of my present invention is to render said meter more positive and more accurate 15 and reliable in its operation and free from pulsations or noise in its actions, which object I attain, first, in an improved form of the rotary piston and in novel devices for positively maintaining the movable partitions or gates 20 in contact with said piston, and, secondly, in the arrangement of auxiliary discharge channels leading from the space between the movable gates through the cover of the case and to the induction-port of the case, all as hereinabove more fully described, and specifically set forth in the claims.

In the annexed drawings, Figure 1 is a transverse section of my improved water-meter. Fig. 2 is a longitudinal section on line xx ; Fig. 30 1. Fig. 3 is a transverse section showing the piston in a different position. Fig. 4 is a detached face view of one of the heads of the case. Fig. 5 is a sectional view of one end of the piston and adjacent end of the case, showing the auxiliary discharge-opening from the case between the two gates; and Fig. 6 is a detached perspective view of the piston.

Similar letters of reference indicate corresponding parts.

40 A represents the shell or case containing the mechanism of the meter. The lower and greater portion of the interior of said case is of cylindrical form, and the upper portion is formed with a cavity, A', in the center of one side of which is the induction-port B, and from the latter projects the screw-threaded thimble for the attachment of the water-pipe. Beneath the opposite side of the cavity A', and slightly above a point diametrically opposite the in-

duction-port B, the case A is provided with 50 the eduction-port C, from which also projects a thimble for the attachment of the water-discharge pipe.

P denotes the rotary piston, which is pivoted to the ends of the case A, central of the 55 cylindrical portion thereof. Said piston is of the form of a hollow cylinder, from two diametrically opposite sides of which project two wings or flanges, P', extending from end to end of the piston and having their longitudinal 60 outer edges in proximity to the cylindrical portion of the case A. Each of said wings is formed with recesses r r' at opposite sides thereof and extending from the free edge of the wing part way toward the cylindrical portion 65 of the piston. The recesses r r' on one side alternate with those on the other side in their relative positions, and the recesses on one and the same side of the two wings P' are in line with each other. The sides of the wings P', 70 which face in the direction in which the piston rotates, and which will hereinafter be referred to as the "front" of the wings, have the portion adjacent to the free edge convexed and joined with the cylindrical portion of the piston by 75 a reverse-curved or slightly-concaved portion, for the purpose hereinafter explained.

D D' represent two gates or movable partitions extending from end to end of the case 80 A and parallel with the axis of the piston. Said gates are hinged to the interior of the case by cylindrical enlargements along one of the longitudinal edges of the gates fitted to corresponding sockets, which are also extended from end to end of the case and form water-tight hinges for the gates. One of these gates is arranged along the side of the cavity A' farthest from the induction-port B, and the other gate, D, is located between the gate D' and the induction-port and in proximity to the latter. The free edges of both gates are inclined toward the induction-port side of the case, and are required to be held in constant contact with the sides of the piston P. This I have heretofore accomplished either by 95 weighting the free edges of the gates, so as to hold them down by gravity, or by springs pressing on the gates; but in practice I have found

that in either case the action of the gates was not sufficiently reliable, and I therefore have now devised more positively-operating means for maintaining the gates in contact with the 5 piston, said means consisting of levers l l , which are pivoted at or near their centers to the interior of the case A, preferably at the center of the length of the latter, and have their ends curved toward the piston P and 10 gates D D', so that one end of said levers will be impinged and crowded outward by the wings P' traversing the same during the rotation of the piston P, and the opposite end of the lever will thereby be pressed upon the 15 gate and thus force the same toward the piston and hold it in contact therewith.

At opposite sides of the gate D, and outside of the periphery of the cylindrical portion of the piston, are two ports, I I, in the inner side 20 of each end plate or head of the case A, and inside of said head are formed two channels, which converge and terminate in two ports, I' I', side by side, with a partition between them in the same side of the head and inside of the 25 periphery of the cylindrical portion of the piston P, and in the ends of said portion of the piston, and at points diametrically opposite each other, are passages n n, coinciding with the two ports I' I'.

30 The operation of my improved meter mechanism thus far described is as follows: Assuming the piston P to stand in the position shown by full lines in Fig. 1 of the drawings at the time when the water is started to flow from 35 the eduction-port C of the case A, the water entering the case A through the induction-port B will exert its force on the gate D and on the wing P', which at that time lies in front of said gate. The gate, being held in contact 40 with the cylindrical portion of the piston, resists the passage of the inflowing water toward the cavity A' and throws the entire force of the water on the aforesaid wing P' of the piston, and thereby causes said piston to be 45 rotated on its axis. As the said wing traverses the eduction-port C the water back of the wing will emerge through the said port. Simultaneously with this movement of the piston the second wing, P', passes the gate D, and 50 when said wing arrives at the position indicated by dotted lines in Fig. 1 of the drawings a portion of the water entering the case A through the induction-port B escapes through the recesses r' r' in the back of the wing P', and thus said portion of water enters the recess A'. The pressure of the water on the 55 wing P' impels the piston in its revolution, and as the wing P' traverses the free end of the lever l the opposite end of the latter is caused 60 to press on the gate D, so as to hold it in contact with the piston while the wing P' moves from it. As the cylindrical portion of the piston approaches said gate the latter swings toward the cavity A' and entraps therein the 65 water which has entered through the recesses r' in the back of the wing P'. The gate D, being still under the pressure of the lever l,

causes said gate to impart pressure to the entrapped water, which, however, is immediately released by the passages n n in the ends 70 of the piston coming in coincidence with the ports I' I' in the heads of the case A, which allows the said water to escape from the cavity A' through one of the ports I, then through 75 one of the channels inside of the head and through one of the ports I', thence through the passage n in the end of the piston, then back through the other channel in the head, and through the port I back of the gate D', from whence it passes through the eduction-port C. It will be observed that during this 80 movement the gate is operated positively by the lever l and is relieved from back-pressure by the release of the entrapped water, and by the hereinbefore-described peculiar curvilinear 85 front face of the wing P' the gate receives the pressure from the lever l gradually, and when applied said pressure is maintained uniform; hence the operation of the meter is positive, accurate, and free from pulsations. 90

I provide the case A with a supplemental cavity, G, similar to that shown in my prior patent hereinbefore referred to, for the collection of sediment which may accompany the water entering the case. Said supplemental cavity is provided with a discharge-opening 95 through which to remove the sediment and is closed by a removable stopper.

The registering mechanism is inclosed in a supplemental case, A'', secured to the case A. 100 Said mechanism may be of any suitable or well-known construction, and as it does not constitute any part of my present invention, and is immaterial to the proper understanding of the improvements herein described, it is 105 deemed unnecessary to describe said registering mechanism. It receives its motion from a helical thread on one of the trunnions of the piston P engaging a pinion, v, on the end of a shaft, w, which, by means of a gear on the 110 opposite end of said shaft, transmits motion to the train of gearing of the registering mechanism.

Having described my invention, what I claim as new, and desire to secure by Letters 115 Patent, is—

1. In combination with the case A A', rotary piston P P', and gates D D', the levers l l, pivoted to the case and having one end engaging the piston and the opposite end bearing on the gates, substantially as set forth and shown. 120

2. In combination with the case A, provided with the cavity A', rotary piston P P', and gates D D', the heads of the case provided with ports I I, and with convergent internal passages terminating in ports I' I', and passages in the ends of the piston coinciding with the ports I' I', substantially as described and shown. 125

3. In combination with the case A, provided with the cavity A', the piston P, having wings P' P', with reverse-curved front faces, the gates D D', the levers l l, for operating said 130

gates, the heads of the case provided with ports I I, and with convergent internal passages terminating in ports I' I' and passages in the ends of the piston coinciding with the 5 ports I' I', all constructed and combined substantially in the manner and for the purposes set forth.

In testimony whereof I have hereunto signed

my name and affixed my seal, in the presence of two attesting witnesses, at Syracuse, in the 10 county of Onondaga, in the State of New York, this 20th day of May, 1886.

FREDERICK W. TUERK, JR. [L. S.]
